Des. 212,497
Patented Oct. 22, 1968

212,497

FISH SCALER OR SIMILAR ARTICLE

James N. Brophy, 180 Prospect St.,
Wakefield, Mass. 01880

Filed Sept. 22, 1967, Ser. No. 8,689

Term of patent 14 years

(Cl. D44—29)

FIG. 1

FIG. 2

FIG. 3

FIG. 4

FIG. 5

FIG. 1 is a view in perspective of a fish scaler or similar article embodying my new design;

FIG. 2 is a side view thereof;

FIG. 3 is a front end view thereof;

FIG. 4 is a rear end view thereof; and

FIG. 5 is a bottom plan view thereof.

The dominant features of my design reside in the portions shown in full lines.

The electric cord is shown broken away in the various views for convenience of illustration.

I claim:

The ornamental design for a fish scaler or similar article, substantially as shown and described.
